UNITED STATES PATENT OFFICE.

ERNEST PINOCHE, OF COUSANCELLES, FRANCE, ASSIGNOR TO FERNAND RADELET, OF BRUSSELS, BELGIUM.

APPARATUS FOR THE SEPARATION AND CLASSIFICATION OF SOLID MATERIALS.

Application filed January 31, 1923. Serial No. 616,058.

To all whom it may concern:

Be it known that ERNEST PINOCHE, citizen of the French Republic, residing at Cousancelles, Meuse, France, has invented 5 certain new and useful Improvements in Apparatus for the Separation and Classification of Solid Materials, of which the following is a specification.

The present invention has reference to an 10 apparatus for separating and classifying mixtures of solid materials in a divided condition in suspension in a liquid, and more particularly mixtures of materials constituting ores and coal.

15 The chief object of the invention is to combine the action of centrifugal force with that of gravity in an apparatus of small size having a great output, in order to obtain an efficient separation and classification 20 of the materials according to their equivalence or their density. By "equivalent" particles are to be understood particles which, although of different sizes and densities, are adapted to fall with the same 25 velocity within the liquid in which they are treated.

The apparatus according to this invention comprises a rotor composed of one or more separating sheaths arranged symmetrically in relation to an axis of rotation and each comprising a helico-truncated part 30 connected to a central feed conduit and merging into a truncated part in which is effected the separation of the materials in suspension in the liquid. The helico-truncated part is intended on the one hand to guide the material to be separated to the top of the truncated part and to distribute liquid over the whole height of the latter, 35 and on the other hand to impart to the materials and to the liquid sufficient speed in order that the separation can be effected in the truncated portion under the action 40 of centrifugal force. For this purpose the helico-truncated portion is divided into curved channels by means of ribs or partitions. The upper channel or passage receives a mixture of materials to be separated and liquid, whilst the following channels 45 are fed solely with liquid. In the truncated part the ribs or partitions are extended by means of ribs or partitions which are incomplete or suitably perforated so as to permit of the passage of the material from one 50 channel or conduit to the other.

The apparatus thus constructed is adapted to work in a continuous manner, the classified products being collected in different conduits in a casing surrounding the rotor. The rate at which the liquid flows may be 60 varied by means of valves or the like and a variable and sufficiently long time can thus be allowed for the separation in order to obtain a very efficient classification.

The accompanying drawings show diagrammatically by way of example an apparatus provided with two sheaths constructed according to the invention.

Figure 1 is an elevation of the apparatus mounted upon its driving shaft.

Figure 2 is a partial plan view of the apparatus.

Figure 3 shows in vertical section the relative arrangement of the discharging nozzles and the surrounding casing.

Figure 4 shows on a smaller scale the form generally adopted for the classifying sheath.

Figure 5 shows a modified form of said sheath.

Figure 6 is a conical section, as on line A—B of Figure 4, showing modified means for varying the rate of flow in the apparatus.

The apparatus shown in the accompanying drawings comprises two separating sheaths each composed of a helico-truncated portion *a—b* and of a truncated portion *c—d* the walls *p* and *q* of which (Fig. 4) are two co-axial conical surfaces.

The helico-truncated portion *a—b* may be considered as an element of a helico-centrifugal pump element having a large output and its object is to impart to the water and to the materials in suspension therein the required rate of flow. It is provided with internal partitions or guiding ribs *e, f, g* adapted to prevent the formation of eddies; the streams of fluid are thus guided as in the narrow channels of a helico-centrifugal pump.

The conical part *c, d* which is of constant section, receives the water and the materials coming from *a—b*; it is also provided with guiding ribs *e', f', g'* which form extensions of the guiding ribs *e, f, g*; but these ribs *e', f', g'* do not form complete partitions; they may bear only on the inner wall *q* of the sheath so as to occupy a part of the section thereof or else, bearing upon both walls *p* and *q*, they may be provided with a number of apertures of a larger diameter than the

calibre or size of the particles of material to be treated. These incomplete partitions, whatever be their form, are intended to permit the particles or grains in suspension in the water to travel in the sheath, under the influence of the centrifugal force, in a direction oblique to the direction of the streams of fluid, these latter remaining always in a state of guidance.

10 The discharge end of the truncated part may be closed, for example by means of a plate *h* provided with nozzles *i*, so as to distribute separately in as many classes as desired the materials which have been treated.

15 The accompanying drawing shows four nozzles but this number may vary according to requirements. The nozzles *i* may be provided with valves *r* permitting of controlling the output by suitably varying the rate

20 of flow in the sheath.

Instead of the plate *h* and its nozzles other means for varying the rate of flow of the liquid may be employed, as for instance a hinged plate or lip *s* (Fig. 6) extending 25 over the whole height of the discharge section of the truncated part so as to simultaneously regulate the outlet orifices of all the channels formed by the ribs *e'*, *f'*, *g'*.

At its upper or inlet end the helico-truncated part of the sheath is connected to two concentric feeding tubes *j* and *k*. The tube *k* is connected to the upper channel only of the helico-truncated part and it is used for introducing into the apparatus a stream of 30 water carrying the material to be treated. The tube *j* is adapted to feed water for diluting purposes to all the other channels of the helico-truncated part.

Figure 4 shows the general form adopted 40 for the separating sheath and Figure 5 is a modification of this form in cases where the difference between the densities of the materials to be treated is small.

The operation of the apparatus is as follows:

The rotor receives from its driving shaft *l* a rotary motion, for example in the direction of the arrow (Figure 2). The divided materials to be treated are introduced into the helico-truncated part through the tube *k* and remain separated by the rib *g* from the diluting water fed through the tube *j* until they enter the top of the truncated part. Starting from this point the materials will be influenced by the action of 50 centrifugal force, and as a result of the communication existing between the channels or passages limited by the ribs *e'*, *f'*, *g'*, they will separate according to their equivalence or to their density, along the generatrix of the truncated sheath, while they are being carried forward by the flow of water. On leaving the truncated sheath the materials issuing from the different channels 60 therein will be distributed to a circular cas-

ing *n* divided into concentric channels *m*, corresponding in number and position to the channels of the sheath and adapted to convey the classified materials to collecting basins.

If the materials treated are in grains of different size the classification will be effected according to their equivalences, and if the grains are substantially of the same size they will be classified according to densities. The classification by equivalences may be followed by a fresh treatment to obtain a classification by densities. For this latter treatment it will be advantageous to increase the rate of flow of the liquid by increasing the discharge section of the truncated sheath. By suitably varying this section and the speed of rotation the apparatus may be adapted to the treatment of materials of a widely different character. It will be apparent that the apparatus may be constructed with a greater number of sheaths arranged symmetrically around the axis of rotation and that modifications of construction may be applied without departing from the scope of the invention.

I claim:

1. In apparatus for the separation and classification of solid materials, the combination of a rotor comprising a sheath having a conical portion, means for feeding the materials to be treated to the top of said conical portion, and means for feeding liquid over substantially the whole height of said conical portion.

2. In apparatus for the separation and classification of solid materials, the combination of a rotor comprising a sheath having a conical portion, means for feeding the materials to be treated to the top of said conical portion, means for feeding liquid over substantially the whole height of said conical portion, and means at the discharge end of said conical portion for varying the rate of flow of the liquid in said sheath.

3. In apparatus for the separation and classification of solid materials, the combination of a rotary shaft, a rotor on said shaft comprising a sheath, said sheath having a truncated portion with co-axial conical walls, means for feeding the material to be treated to the top of said truncated portion, means for feeding liquid over substantially the whole height of said truncated portion, and means in said truncated portion for guiding the liquid parallel to the rotation of the sheath while allowing of the solid materials moving transversely thereof under the action of centrifugal force.

4. In apparatus for the separation and classification of solid materials, the combination of a rotor comprising a sheath having a helico-truncated portion merging into a truncated conical portion, means for separately feeding the solid materials and liq-

uid to said helico-truncated portion, and means in said helico-truncated portion for guiding the solid materials to the top of said truncated portion and for distributing 5 the liquid over substantially the whole height of said truncated portion.

5. In apparatus for the separation and classification of solid materials, the combination of a rotor comprising a sheath having a helico-truncated portion merging into a truncated conical portion, concentric pipes arranged axially of said rotor for separately feeding the solid materials and liquid to said helico-truncated portion, a partition in 10 said helico-truncated portion for guiding the solid materials to the top of said truncated portion, and incomplete partitions in said truncated portion allowing the solid materials to travel transversely of the 15 sheath under the action of centrifugal force.

6. In apparatus for the separation and classification of solid materials, a rotor comprising a sheath having a truncated portion with co-axial conical walls, means for 20 feeding the solid materials near the inner edge of said truncated portion, means for feeding liquid over substantially the whole height of said truncated portion, incomplete partitions in said truncated portion allow- 25

ing the solid materials to travel towards the 30 outer edge of said truncated portion, and means for varying the discharge section of said truncated portion.

7. In apparatus for the separation and classification of solid materials, a rotor comprising a sheath having a helico-truncated portion merging into a truncated conical portion, partitions dividing said sheath into a number of substantially parallel curved channels, the channels in said truncated 40 conical portion being connected with one another, means for feeding the solid materials to the inner channel of said helico-truncated portion, means for feeding liquid to the other channels of said helico-truncated portion, a stationary circular casing surrounding said rotor, and partitions dividing said circular casing into a series of 45 collecting channels corresponding in number and in position to the channels in said 50 sheath.

In testimony whereof I have affixed my signature.

ERNEST PINOCHE.
